(57) **CLAIM**

I claim the ornamental design for a garden implement, as shown and described.

DESCRIPTION

FIG. 1 is a perspective view of a garden implement showing my new design in a position of use. The broken line portion is for illustrative purposes only and forms no part of the claimed design;

FIG. 2 is a top plan view thereof;

FIG. 3 is a bottom plan view thereof;

FIG. 4 is an elevational view of one side thereof;

FIG. 5 is an elevational view of the other side thereof;

FIG. 6 is a front elevational view thereof; and,

FIG. 7 is a rear elevational view thereof.
